INSULATED PAIL OR THE LIKE

Arthur H. Payson, Norwich, Conn., assignor to The American Thermos Products Company, Norwich, Conn., a corporation of Ohio

Filed Apr. 11, 1958, Ser. No. 50,434

Term of patent 14 years

(Cl. D58—17)

FIG. 1

FIG. 2

FIG.4

Fig. 1 is a top plan view of an insulated pail or the like showing my new design;

Fig. 2 is a front elevation thereof;

Fig. 3 is a sectional view on line 3—3 of Fig. 1; and Fig. 4 is a sectional view on line 4—4 of Fig. 1.

The dominant features of the design reside in the portions shown in full lines.

The rear of the pail, which is not shown, is the same as the front, which is shown.

I claim:

The ornamental design for an insulated pail, or the like, substantially as shown and described.
